UNITED STATES PATENT OFFICE.

ENRICO MORELLI, OF CINCINNATI, OHIO.

STUCCOING AND PLASTERING MACHINE.

Application filed February 18, 1925. Serial No. 8,901.

To all whom it may concern:

Be it known that I, ENRICO MORELLI, a subject of the King of Italy, residing in Cincinnati, county of Hamilton, State of Ohio, have invented certain new and useful Improvements in Stuccoing and Plastering Machines, of which the following is a specification.

My invention relates to building machines in general and particularly to machines for applying plaster or stucco or the like to the walls of buildings.

It is my object to construct for this purpose a machine which will mechanically apply plaster or stucco to the walls of a building which will not require any manual effort on the part of the operator, aside from the necessary adjustment of valves, levers and starters which control the operation of the machine. It is further my purpose to provide in the delivering orifice a mechanically operated trowel to move the plaster onto the wall and to so arrange an air nozzle that the compressed air from it will keep the trowel clean and at the same time co-operate with the trowel in forcing the plaster into the lath on the walls. It is further my object to electrically control the mechanism which operates the delivering nozzle so that when the nozzle is at the high and low limits of movement the mechanism will be stopped. Further, it is my object to provide in a supporting structure for the machine a tilting device which will correct for any unevenness in the floor in front of the walls which the machine is working on.

To accomplish these several purposes I have constructed a machine in accordance with the following description: Referring to the drawings forming part of this specification, Fig. 1 represents a perspective view of the assembled device with some of the co-operating parts diagrammatically shown. Fig. 2 is a sectional view through the feeding nozzle. Fig. 3 is a detail view of the mechanical device which ejects the plaster, and Fig. 4 is a detail view of the air supply device which co-operates with the mechanical device shown in Fig. 3.

Generally indicated at 1 is a framework which in a small machine is composed of vertically extending members 2 which are bolted or riveted to horizontally extending members 3 forming a rigid structure. For use on very high walls the vertically extending members will be provided with ex-

tensions, with faces aligned with the faces of the vertical members shown. As these extensions involve such a simple mechanical principle I have not shown them in the drawings in this application. The frame described which may conveniently be called the vertical frame is supported at the base by a secondary frame with bars 4 which are bolted to longitudinal members 5 to form another frame structure which may conveniently be called the horizontal frame. Aligned with the lower supporting members of this frame and supporting the castors 6 of the horizontal frame is another rectangular shaped structure composed of lateral bars 7 and longitudinal bars 8. These two structures are thus in the form of open crates. From the top members of the horizontal frame bars 9 extend diagonally to the top of the vertical frame and are secured thereto by bolts or rivets. A plurality of platforms may be laid across the horizontal frame as the platform shown in the drawings at 10. These platforms may be of any suitable size or strength and serve, as will be hereinafter described, to support the motors and auxiliary parts necessary for the operation of the machine.

The upright extending members of the vertical frame are in the illustration shown disposed as channel irons and extending lengthwise between the side openings of the channels a nozzle supporting platform 11 is disposed with bars extending out beyond the faces of the channels and bent over, bearing on them, as shown at 12, so that the platform is retained within the channels slidably, with, however, perfect freedom to move upwardly and downwardly in the channels.

In the center of the channel the platform is secured with a cable 13 which passes up over a pulley 14 journaled in bearings fastened at the top of the diagonal support bars 9. A motor 15 with a cable spool 16 attached to its shaft operates the cable to raise and lower the nozzle platform as may be readily understood.

In case there is no convenient source of air pressure where the machine is being used I have made provisions for an air supply device to fit conveniently on one of the platforms 10 which is composed of an independent motor 17 which operates a small compressor 18 which delivers compressed air to a pressure tank 19. A flexible tubing

from this pressure tank, therefore, may be used to supply the plastering nozzle.

It is essential for successful results that the platform 11 be adapted to move vertically up and down facing the wall to be plastered and as the horizontal frame, if it stood on the floor, would necessarily hold the vertical frame at right angles to itself and if the floor was not level it could not hold the vertical frame in other than a position at right angles to the position in which it stood. Consequently in order to provide for a perfect way of leveling the horizontal frame I have formed what may be called the base frame which is composed, as noted, of lateral beams 7 riveted to lengthwise beams which are disposed as a track under castors 6 which are fastened to the bottom bars of the horizontal frame. Jacks 25 fit under the base frame and through them the platform may be leveled to an exact position. The track and castor members also provide a convenient means of moving the plastering nozzle along the wall which is being plastered.

25 The structures hereinbefore described are merely preferred forms of simply constructed parts and many changes will readily occur to those skilled in this art for providing a different disposal of parts. It is not my purpose to claim any particular structure except in so far as it is necessary to adjust the machine to operate successfully as will be hereinafter explained.

On the platform 11 in an extended position toward the back of the channels a small motor 24 is disposed which has an eccentric pivot and the gear teeth on the rack are thus moved forwardly and backwardly imparting movement to the gear wheel 26 which is journaled on the outside frame of the nozzle and imparts its motion to a gear 27 which is mounted on the trowel shaft. The plastering nozzle is composed of a supply box or tank 28 which may conveniently have a paddle mounted on a shaft 30 journaled in the ends of the box in journals 31. To have this paddle serve to contact with the plaster in the box and exert a force to push the plaster out of the box a spring 32 which may be of the kind used for screen doors is attached to a pin 33 extending from the paddle shaft. The spring passes about the shaft several times and the end may be attached to another pin 34 secured in the side of the box in a position farther around than the extreme limit of throw of the paddle when the box is empty.

A passage-way 35 opening from the supply box extends to the nozzle compartment. 60 Mounted longitudinally in this compartment a hollow shaft 36 is journaled with the gear 27 mounted on it. The rack which controls the movement of this shaft is adapted to move it in an arc which is approximately one-third of a circle. Fixed to the shaft ex-

tending the length of the discharging aperture 37 are two trowels 38 which form a hollow V shaped compartment 39. The shaft as has been noted is hollow and a slot extends throughout its length which releases the air from the hollow air pipe 40 which is mounted within it. The air pipe also has a slot 41 extending throughout its length within the discharging aperture. The air pipe or shaft is non-rotatively mounted so that the air within the air pipe will only be released when the two slots are in co-operating position and alignment. The slot 41 is positioned so that it will allow the air to escape from the pipe only when the trowel members are in position to force plaster from the discharging orifice. The slot may, of course, be formed with a series of interspaced holes instead of a continuous slot.

When the trowels pass back into the passageway 35 the slots are not in alignment and no air blows out through the nozzle.

The operation of the machine is simple. The base frame is moved to position facing the wall to be plastered and leveled so that the longitudinal frame will be parallel with the wall. In case the wall is not in an exact vertical plane the adjustment of the base frame will also make allowance for it. The switches controlling the operation of the motor which raises the nozzle platform are then turned on and the nozzle will start moving up along the face of the wall. The supply tank which may be filled from a bucket or pipe from the box or tank where it has been previously mixed is then put in operating condition by releasing the lock 42 which retains the paddle in inoperative position. The paddle pushes against the plaster in the supply box and forces it down through the outlet passage into the nozzle compartment. The rack bar moves the trowels back into the compartment and an amount of plaster depending on the size of the parts will be forced outwardly. As the trowels move toward the position of their extreme outward throw the air released by the co-operating notches is forced out from the V shaped opening between the trowels and forces the plaster into the lath on the wall. The nozzle platform is meanwhile started in motion. When the nozzle has plastered an area equal to the width of the nozzle and extending from the floor to the ceiling the horizontal frame is moved to a position where the nozzle will plaster another strip alongside of the first. A trowel 43 and a brush 43^a disposed either above or below the trowel is attached to the frame of the nozzle by an adjustably mounted rod 44 and on this second operation of the machine covers the same area on which the first strip of plaster was laid. Thus every completed movement of the nozzle from the bottom to the top of the wall not only lays one strip

of plaster but it smooths over the adjoining preceding laid strip.

Having thus described my invention, what I claim as new and desire to secure by Letters Patent, is:

1. In a device of the character specified comprising adjustable supporting frame members with a vertical frame member with a nozzle platform slidably retained thereon, means for adjusting the adjustable frame members whereby said vertical frame is aligned to operating position, means for retaining on the frame members a motor operating said nozzle platform, and a nozzle for applying plaster mounted on the nozzle platform, said nozzle comprising a supply box and a discharging orifice member, said supply box with means therein for forcing the plaster from the box into the discharging orifice member, said discharging orifice member with means therein for forcing plaster onto a wall, said last mentioned means comprising in combination compressed air and mechanically moved members.

2. In a plastering and stuccoing machine, frame members adapted to support a vertically extended frame with means for tilting said first mentioned frame members whereby said vertical members may be brought in parallel alignment with a walled surface, said vertically extended frame adapted to slidably retain a nozzle platform, said nozzle platform adapted to be moved in parallel alignment with a walled surface throughout the length of the vertical frame, a nozzle mounted on said platform with a motor for operating flat blades within the nozzle.

3. In a plastering and stuccoing machine frame members adapted to support a vertically extended frame with means for tilting said first mentioned frame members whereby said vertical members may be brought in parallel alignment with a walled surface, said vertically extended frame adapted to slidably retain a nozzle platform, said nozzle platform adapted to be moved in parallel alignment with a walled surface throughout the length of the vertical frame, a nozzle mounted on said platform with a motor for operating flat blades within the nozzle, said flat blades disposed on a rock shaft forming an opening between them and an air pipe disposed in non-rotative position within said rock shaft.

4. In a plastering and stuccoing machine frame members adapted to support a ver-

tically extended frame with means for tilting said first mentioned frame members whereby said vertical members may be brought in parallel alignment with a walled surface, said vertically extended frame adapted to slidably retain a nozzle platform, said nozzle platform adapted to be moved in parallel alignment with a walled surface throughout the length of the vertical frame, a nozzle mounted on said platform with a motor for operating flat blades within the nozzle, said flat blades disposed on a rock shaft forming an opening between them and an air pipe disposed in non-rotative position within said rock shaft, with openings in the air pipe and means for selectively aligning said openings on hollow rock shaft carrying the flat blades in the forwardly extended position of said blades.

5. A plastering device comprising a supply box with an outlet aperture therein and means causing the discharge of material within the supply box through the outlet aperture, and a discharging compartment connected with the supply box outlet aperture with combined mechanical and pneumatic means in the discharging compartment for ejecting the material from said compartment onto a wall.

6. A plastering device comprising a supply box with an outlet aperture therein and means causing the discharge of material within the supply box through the outlet aperture, and a discharging compartment connected with the supply box outlet aperture with combined mechanical and pneumatic means in the discharging compartment for ejecting the material from said compartment onto a wall, and means for moving said plastering device in a plane parallel to a walled surface.

7. A plastering device comprising a supply box with an outlet aperture therein and means causing the discharge of material within the supply box through the outlet aperture, and a discharging compartment connected with the supply box outlet aperture with combined mechanical and pneumatic means in the discharging compartment for ejecting the material from said compartment onto a wall, and means for moving said plastering device in a plane parallel to a walled surface, with auxiliary means for smoothing over a plastered surface adjacent the area traversed by the nozzle.

ENRICO MORELLI.
